TURBINE ROTOR

Oscar Anton Wiberg, Finspong, Sweden

Application March 27, 1944, Serial No. 528,327

In Sweden February 24, 1943

4 Claims. (Cl. 253—77)

This invention relates to turbine rotors of the type comprising a disc and a set of blades fixed to the periphery thereof.

In manufacturing turbine rotors of this type according to a well-known method, the blades are connected to the disc by means of a straddling engagement between the base-portions, or feet, of the blades and the peripheral portion of the disc, or vice versa, and sealed in this engagement by means of peripherally extending claw-shaped projections, or lugs, formed on the contact surfaces of said feet which engage similar lugs formed on the contact surfaces of the peripheral disc portion. The most usual way in which to effect this fixing of the blades to the supporting disc comprises deflecting the forked ends, or prongs, of the blades or disc, causing the deflected prongs to straddle the peripheral portion of the disc or the blade feet, as the case may be, and the associated lugs, and then forcing the prongs together so as to cause them to firmly embrace the member or members in engagement therewith. Since this method may give rise to certain risks as to the strength of the connection it has been proposed to fix the blades without deflecting the prongs of the forked member or members. Such a proposal is disclosed in the British Patent No. 461,058. According to said patent the lugs of the blade feet extend along a certain portion of the peripheral length of the blade feet only, whereas the annular projections or lugs of the peripheral portion of the disc are cut away at one or more places to an extent corresponding to the peripheral length of the lugs of the blade feet. Thus, at said place or each of said places an inlet passage will be obtained through which the blade feet with their lugs may be put onto or inserted into the peripheral portion of the disc without requiring any deformation of the blade feet, nor of the disc. As soon as an individual blade has been mounted in this way, it has to be displaced peripherally so as to bring its lugs into engagement with those of the disc. The mounting of the last blade being completed, all of the blades have to be pushed back around the disc by an amount corresponding to the peripheral length of the lugs of a blade foot in order that also the last blade, the lugs of which extend from the opposite end of the blade foot as compared with the lugs of the other blades, may be adjusted to a position in which its lugs will engage the lugs of the disc. According to said patent the lugs of the blade feet extend along $\frac{2}{3}$ of the peripheral length of said feet. Consequently, each individual blade may be sealed to the disc

along said $\frac{2}{3}$ of the peripheral length of the blade foot only. In practice, however, this has proved quite sufficient.

The method above described for fixing turbine blades to a turbine disc without deforming the blades, nor the disc, has proved difficult owing, essentially, to the said pushing back of the entire set of blades, resisted as it is by the high friction appearing between the blade feet and the peripheral portion of the disc. Furthermore, said method cannot satisfactorily safeguard against a certain play within the blade ring.

The present invention has for its object to facilitate the fixing of the blades to the disc, while positively avoiding any play between the blade feet and securing an increased strength and solidity of the blade ring as a whole.

The invention is characterized, chiefly, by the provision of a main group of blades having lugs extending along a portion only of the peripheral length of the feet from one end thereof, a minor group of blades having feet corresponding in position and peripheral length to the respective lugs only, the remainder of the feet having been cut away, an additional blade having a foot of the same peripheral length as the said first-mentioned blades and lugs thereon extending along a portion of the peripheral length of the foot from the opposite end thereof as compared with the lugs of said first-mentioned blades, and means to maintain the blades of said minor group in predetermined positions with relation to each other and to the said additional blade, said disc having an inlet passage or passages to allow the applying of the blades to the periphery of the disc.

The blades of said minor group may be pushed together to one side of the inlet passage within the range of the periphery of the disc available for the reception of these blades. By these means, the additional blade having reversely positioned lugs may be inserted through the inlet passage and displaced peripherally to its final position on the other side of the inlet passage into engagement with the lugs of the periphery of the disc without requiring the entire set of blades to be pushed back. Then, it is only required to move the blades of the minor group apart, and fix them in exact relative positions by means of distance pieces which correspond in size and form to the cut away portions of the blade feet and like these have no lugs. It is preferred to make the distance piece to be last inserted tapered or wedge-shaped at its end, so that it may be forced into its respective space in order to remove any

play that may exist within the blade ring. Thus, in the method according to the invention the adjustment required subsequent to the insertion of all the blades is limited to the few blades of said minor group, whereas all the other blades are allowed to remain in their original set positions.

In the accompanying drawings, a first embodiment of the invention is shown in Figs. 1, 3, 5 and 7, which figures illustrate various stages of the assembling of the turbine rotor the radius of which for the sake of simplicity may be assumed to be infinite and the periphery of which, as a result, may be represented by a straight line. Figs. 2, 4, 6 and 8 show axial sections on the lines II-II, IV-IV, VI-VI and VIII-VIII, respectively, of Figs. 1, 3, 5 and 7, respectively. Fig. 9 shows a corresponding section of a modified embodiment. Figs. 2a, 4a, 6a and 6b are sectional views similar to Figs. 2, 4, 6 and 8 respectively of a modified embodiment of the invention.

With reference to the drawings, the numeral 1 designates the peripheral portion of a turbine disc adapted to be straddled by the fork-shaped feet of the turbine blades to be carried thereby. It is to be noted that the arrangement may be reversed, if desired, without departing from the principle of the invention. Sectional views corresponding to Figs. 2, 4, 6 and 8 respectively, but showing the reverse arrangement in which the turbine disc is provided with the fork-shaped feet which straddle and grip the roots of the turbine blades, are shown in Figs. 2a, 4a, 6a and 6b. The peripheral turbine disc portion carries on both of its sides circumferentially extending claw-shaped lugs 2, pointing inwardly towards the axis of the disc. These lugs are shown in section in Fig. 2 and in side elevation in Fig. 4, but are for the rest merely indicated in Fig. 1 by dotted lines within those ranges where no blades are shown. At one or more places the lugs 2 are cut away so as to form an inlet passage or passages extending in the direction intended for the blades. In the drawings, such an inlet passage is indicated at 3. As shown, said passage extends at right angles to the periphery of the disc, that is to say, in radial direction. If there is but one such passage, all the blades have to be inserted therethrough; in order, however, to reduce the necessary displacement of each blade after insertion, it is preferred to provide a plurality of inlet passages, say, four. In such a case a fourth of the periphery of the disc may be filled with blades through each inlet passage.

Through the inlet passage 3 or each inlet passage I first introduce a number of blades having feet of "normal" type. These blades form what is referred to as the main group of blades in this description. In the case illustrated the blades of the main group are designated by the numeral 4 and are provided with circumferentially extending, outwardly pointing, claw-shaped lugs 5 provided, for instance, on $\frac{1}{3}$ of the peripheral length of the blade feet from one end thereof. After insertion through passage 3, the blades 4 are displaced to both sides of the inlet passage until at one side of the passage (to the left thereof, Fig. 1) a space free from blades remains, the peripheral extent a of which is equal to $\frac{2}{3}$ of the peripheral length of a blade foot, while at the other side of the passage a free space is left, the peripheral extent b of which is equal to $\frac{1}{3}$ of the peripheral length of a blade foot. It is evident, that the peripheral length of the blade foot should bear a predetermined relation to the

peripheral length of the disc in order to permit the arrangement described. This arrangement having been obtained, the positions of the blades 4 of the main group with relation to the inlet passage 3 is the one illustrated in Fig. 1.

Then, I introduce through passage 3 the blades which are referred to as the minor group of blades. Said blades which are designated by the reference numeral 6, are few in number, say, three. They are formed with reduced feet, inasmuch as the portions of the feet not occupied by the lugs have been cut away. After insertion, the blades 6 are displaced onto the space a and pushed together sufficiently to allow the insertion through passage 3 of the additional blade 7. The foot of said blade is of the same peripheral length as the feet of the blades 4 of the main group, but the lugs extend along $\frac{2}{3}$ of the peripheral length of the foot from the opposite end thereof as compared with the lugs of blades 4, that is to say, from the right hand end instead of from the left hand end thereof, as shown in Fig. 3. After insertion, the additional blade 7 is moved onto the space b until it comes into engagement with the last blade 4 on this side of the inlet passage, as shown in Fig. 5. By this means, the lugs of the additional blade 7 are brought into engagement with the lugs 2 of the peripheral disc portion.

Between each two adjacent blades 4 I then insert distance pieces 8 corresponding in size and shape to the cut away portions of the blade feet, and between blade 7 and the adjacent blade 6 I introduce a distance piece 9. None of said distance pieces is provided with lugs. In order to facilitate the insertion of the distance piece 9, the latter may be tapered or pointed like a wedge. The distance pieces may be sealed in their positions by means of rivets 10 or by other appropriate means.

It is to be noted that the invention may also be applied to blades and discs of other profiles than those illustrated in the drawings. An example of such a modified profile is shown in Fig. 9. Here, the blade foot 4 is provided with end flanges 11 engaging inside lateral flanges 12 formed on the peripheral disc portion. By this means deflection of the prongs of the forked blade foot may be positively avoided.

What I claim is:

1. In a turbine rotor of the type set forth, a turbine disc, a set of turbine blades having feet spaced apart attached to the periphery of the turbine disc by a straddling engagement between the feet of the blades and the peripheral portion of the disc, peripherally extending claw-shaped lugs and corresponding grooves formed in the abutting surfaces of said feet and said peripheral portion for sealing the blade feet and disc in said engagement, said set of turbine blades comprising, in series, a main group of blades the feet of which are formed with lugs and grooves along a fraction of their peripheral length as reckoned from one peripheral end of the feet, a minor group of blades from the feet of which the lug and the groove free portions are cut away, a final blade having a foot of the same peripheral length as the said blades of the main group and having lugs and grooves on said foot which extend along a fraction of the peripheral length thereof from the opposite peripheral end thereof as compared with the lugs and grooves of the blades of the main group, separate distance pieces inserted in the place of the cut away portions of the feet of the blades of said minor group, and the lugs of the peripheral

portion of the disc being cut away along a peripheral length corresponding to that of the lugs of the blade feet, so as to form an inlet passage for application of one blade at a time to the periphery of the disc.

2. In a turbine rotor according to claim 1, and in which the distance pieces for replacing the cut away portions of the feet of the blades of the minor group are of the same profile as the cut away portions of the feet of said blades and of 10 the same peripheral length as said cut away portions.

3. In a turbine rotor according to claim 1, and in which the distance piece adapted to replace the cut away portion of the feet of that blade of the minor group which is situated next to the said final blade, is wedge-shaped in order to facilitate its insertion in place.

4. In a turbine rotor according to claim 1, and in which means is provided for sealing said distance pieces in their positions.

OSCAR ANTON WIBERG.
